UNITED STATES PATENT OFFICE.

CHARLES HENRY KELLY, OF MUNCIE, INDIANA, ASSIGNOR TO MUNCIE OIL ENGINE COMPANY, OF MUNCIE, INDIANA, A CROPORATION OF ILLINOIS.

INTERNAL-COMBUSTION ENGINE.

1,173,111.

Specification of Letters Patent. Patented Feb. 22, 1916.

Application filed July 5, 1913. Serial No. 777,401.

To all whom it may concern:

Be it known that I, CHARLES HENRY KELLY, citizen of the United States, residing at Muncie, in the county of Delaware and State of Indiana, have invented certain new and useful Improvements in Internal-Combustion Engines, of which the following is a specification.

My invention relates to improvements in internal combustion engines and is directed particularly to the provision of a simple and effective means for adjusting or changing the size and capacity of the cylinder, that is, the compression-space of the cylinder.

A further object of this invention is the provision of a series or set of plates, one or more of which is adapted to be detachably secured to the cylinder head whereby the capacity of the compression space may be varied to meet various conditions of working, fuel, etc.

To the accomplishment of the foregoing and such other objects as may hereinafter appear, my invention consists in the construction, combination and arrangement of parts hereinafter described and then sought to be defined in the appended claim, reference being had to the accompanying drawings forming a part hereof and which show an embodiment of my invention applied to an oil engine for illustration purposes only, it being understood that various changes may be made in practice within the scope of the claim without digressing from my inventive idea.

In the drawings: Figure 1 represents a vertical sectional view taken through a portion of the piston, cylinder and cylinder-head of an oil engine, showing my invention in use; Fig. 2 is a perspective view of one of the plates, termed for convenience, compression plates.

It is well known that the different liquid fuels used in internal combustion engines have different chemical properties due to difference in grade, process of refining and origin, and that the flash point varies as well, and for these reasons it is necessary to provide some means for changing the compression, particularly where it is desired to

use a stock engine for different fuels and different grades of fuel. Therefore it is the purpose of this invention to provide a simple and efficient means for varying the capacity of the compression space of the cylinder and thereby varying the compression pressure of the explosive mixture.

Referring now to the drawings, the numeral 1 designates the cylinder, 2 the cylinder head, 3 the piston, 4 the igniter head, 5 the igniter hood, 6 the igniter spoon and 7 the fuel nozzle. These features of construction are well known in this art and do not need further explanation and disclosure.

In Fig. 1 is shown a plurality of plates 8, which are shaped to fit the cylinder head and detachably secured thereto as by bolts 9. It is to be noted that the plates 8 are of different thicknesses. This is for the purpose of readily obtaining any desired size of the compression-space of the cylinder. In assembling, changing or reversing, it is only necessary to remove the cylinder head, when convenient access may be had to the securing means 9.

In the manufacture and sale of engines, a plurality or set of plates is furnished with each stock engine so that the necessary changes may be readily made as desired to meet the varying working conditions.

Another advantageous feature of this invention, is the fact that the plate or plates act as a heat absorbing element, giving out the heat during the compression stroke of the piston and keeping the temperature of the combustion chamber up to the desired point. Also the plates serve as a protecting means or medium for the walls of the cylinder head being positioned between the compression space and jacketed walls of the cylinder head, the difference in the temperature between the jacket and the heat of the explosion being considerable and having an injurious effect on the cylinder head.

What I claim is:

In an internal combustion engine, in combination with a cylinder, an igniter head on one end thereof, an igniter spoon connected to said igniter head and extending into said cylinder, a fuel nozzle entering said cylinder

above said igniter spoon, a plurality of plates adapted to be attached to said end of the cylinder to reduce the compression space thereof, said plates each having a central 5 aperture to permit them to be passed over said igniter spoon, and means for detachably connecting them to said cylinder end.

In testimony whereof I affix my signature, in presence of two witnesses.

CHARLES HENRY KELLY.

Witnesses:

O. G. DEANE,
HENRY BREWER.
